UNITED STATES PATENT OFFICE.

LYMAN CLAPP BAILEY, OF CALAIS, MAINE.

STORE-WINDOW.

SPECIFICATION forming part of Letters Patent No. 293,216, dated February 12, 1884.

Application filed July 10, 1883. (No model.)

To all whom it may concern:

Be it known that I, LYMAN C. BAILEY, of Calais, county of Washington, State of Maine, have invented an Improvement in Store-Windows, of which the following description, in connection with the accompanying drawings, is a specification, like letters on the drawings representing like parts.

My invention relates to an improvement in store-windows, such as commonly used for the exhibition of goods to be seen from the street outside the store, and has for its object to prevent the collection or condensation of moisture and formation of frost upon the window in cold weather. Such condensation of moisture is due to the difference in temperature at the outside and inside of the window, the interior of the building being artificially heated, so that the temperature is much higher within it than at the outside; and the heated interior air coming in contact with the surface of the glass at a much lower temperature gives up its moisture, causing a thick deposit of frost in cold weather, which effectually obscures vision through the window, and, moreover, cuts off a large portion of the light.

My present invention consists in means, hereinafter described, and specifically pointed out in the claims, for keeping both sides of the glass at the same or nearly the same temperature, which I accomplish by providing small inlet-openings at the lower end of the window or sash, to permit the exterior air to enter, and by combining with the window provided with such openings a deflector, by which the current of air thus entering is directed along the interior surface of the glass, preventing the contact therewith of the warmer atmosphere within the building. I also provide a secondary pane of glass or window within the outer window, inclosing a chamber or space of considerable size, and at the upper end of the said secondary window I provide a series of openings or passages, to permit the air to escape from the chamber formed between the two windows, and thus maintain a sufficient circulation in the said space or chamber.

Figure 1 is a front elevation of a window

embodying this invention; and Fig. 2 a vertical section thereof on line *x x*.

The window consists of one or more panes of glass, *a*, inclosed in frame-work *b* in the usual manner, and is provided at its lower end with one or more inlet-openings, *c*, preferably extending for the greater part of its width, and immediately within the said openings is placed a deflector, *d*, consisting of a plate or wing turned upward parallel with the glass at a short distance from its inner surface.

In the construction of store-buildings, the door is frequently recessed or set back a short distance—two or three feet perhaps—from the plane of the front of the building or main window *a*, and the space between the said main window and door is inclosed by another window, *a'*, usually set diagonally between the front window, *a*, and the door, and in this construction the said window *a'* will be provided with a similar inlet-opening, *c'*, having a deflector behind it.

At some distance at the rear of the main window *a*, preferably about at the plane of the door or rear edge of the window *a'*, is placed a secondary pane of glass or window, *e*, (see Fig. 2,) thus inclosing a chamber or air-space, *A*, between the main or outer windows, *a a'*, and the secondary or inner window, *e*; and at its upper portion the said secondary window is provided with one or more passages, *i*, which permit the air to pass between the said chamber *A* and the interior of the store.

In cold weather, when the interior of the store is artificially heated to a much higher temperature than the air outside, the cold air will enter the chamber *A* from the outside, passing through the passage *c*, and being deflected upward along the inner side of the window *a*, as shown by the arrows, Fig. 2, and will thus maintain an atmosphere of substantially the same temperature at the inner and outer surfaces of the said window *a*, which effectually prevents the condensation of moisture or formation of frost upon the said window. The openings at *i* permit proper transfer or circulation of air between the chamber *A* and the interior of the store to effect the

desired result; and by the herein-described construction windows are kept perfectly free from frost or condensation of moisture at all times. While this is especially desirable in windows of stores used for the exhibition of merchandise within the store, the invention is of course applicable to all windows where it is desired to prevent the collection of moisture or frost.

10 I claim—

A store or show window consisting of the fixed exterior window, *a*, having at its bottom the air-openings *c* and the air-deflecting plate

d, arranged before said openings, to direct the incoming air upwardly along the interior surface of the pane and the interior window or partition, *e*, having the openings *i* at the top thereof, substantially as shown, and for the purpose described.

In testimony whereof I have signed my name to this specification in the presence of two subscribing witnesses.

LYMAN CLAPP BAILEY.
